H. A. CARPENTER.
VALVE MECHANISM FOR GAS RETORTS.
APPLICATION FILED JULY 24, 1913.

1,149,026.

Patented Aug. 3, 1915.

UNITED STATES PATENT OFFICE.

HENRY A. CARPENTER, OF SEWICKLEY, PENNSYLVANIA, ASSIGNOR TO RITER-CONLEY MANUFACTURING COMPANY, OF PITTSBURGH, PENNSYLVANIA, A CORPORATION OF NEW JERSEY.

VALVE MECHANISM FOR GAS-RETORTS.

1,149,026.

Specification of Letters Patent. Patented Aug. 3, 1915.

Application filed July 24, 1913. Serial No. 780,898.

To all whom it may concern:

Be it known that I, HENRY A. CARPENTER, a citizen of the United States, residing at Sewickley, in the county of Allegheny and

5 State of Pennsylvania, have invented certain new and useful Improvements in Valve Mechanism for Gas-Retorts, of which the following is a specification.

This invention relates to that type of coal 10 gas generating apparatus wherein communication between a retort and stand-pipe or other gas offtake is controlled by a valve, and has particular reference to improved means for insuring movement of the valve 15 to closed position before opening the retort door, thereby forestalling inadvertent opening of the door when the valve is open, and preventing either escape of gas from the offtake to the atmosphere, or inrush of atmospheric air into the gas offtake.

In the accompanying drawing, which 20 illustrates an application of my invention, Figure 1 is a part plan and a part sectional view of a retort mouth-piece shown in connection with a stand-pipe and with valve 25 mechanism and retort closure means; Fig. 2 is a front elevational view; Fig. 3 is an enlarged side elevational view; and Fig. 4 is a detail view partly in elevation and partly 30 in section, the section being taken on line IV-IV of Fig. 3.

As illustrated and as preferred, the mouth-piece 1 is designed to be connected with a stand-pipe 2. In practice, the stand-pipe 2 is usually interposed between two rows of retorts or between the mouth-pieces 1 thereof, said stand-pipe 2 being provided with openings 3 in opposite faces thereof, respectively designed to communicate with 35 an outlet opening of a nozzle or an extension 4 formed integral with the mouth-pieces. This extension 4 is designed to abut against the stand-pipe and as shown, is of substantially the same height as the mouth-piece but of comparatively short length. The walls of the extension form a chamber of sufficient dimensions to receive a valve and a portion of a valve actuating mechanism, and the chamber so formed is conveniently accessible for cleaning and other 45 purposes through the front opening of the mouth-piece.

As illustrated, the nozzles or extensions 4 are each provided with a seat 5 and with a

flange 6 adapted to be entered in a face of 55 the stand-pipe with the opening 3 of the stand-pipe registering with the outlet passage of the mouth-piece.

Communication between the mouth-pieces and the stand-pipe is controlled by means of 60 a valve mechanism comprising, as illustrated, a ball valve proper 7 adapted when in closed position to rest upon the seat 5 of the extension 4. Said valve 7 is secured on an end of a bent arm 8 by a universal joint 65 connection 9. The arm 8 is secured to or made integral with a horizontally extending shaft 10 projecting outwardly from the mouth-piece and having its bearing in a casting 11. The outer end of the shaft 10 is 70 preferably shaped as shown at 12 to permit a tool (not shown) to be placed thereon by which the shaft 10 together with its arm 8 are moved.

In constructions of this character employing a valve for controlling communication between the retort or the retort mouth-piece and the stand-pipe, it is essential that the space or passage-way through which the gas passes from the retorts to the stand-pipe should be easily accessible, preferably through the outer opening or end of the mouth-piece, for the purpose of cleaning the connection space or passage-way when the valve is closed or seated; and the construction illustrated is particularly adapted 75 for this purpose. The general arrangement above described is also particularly effective in maintaining the valve seat substantially 80 free from deposit. The valve 7, being practically swiveled and movable in an arc toward and away from the seat 5, has a tendency, during its movement toward the seat, to shift its position on the ball 9, the result being that this shift must be corrected 85 by the valve seat in order to permit the valve to properly seat, and this correcting action has the effect of providing a relative movement between the valve and seat such as would remove the deposits on the seat, 90 etc., or render them ineffective to prevent a proper seating of the valve. Furthermore, the valve in its open position is located out of the direct gas path into and through the passage-way, and is consequently not liable 95 to collect deposit, especially as the curved face of the valve extends toward such path.

Located on the shaft 10 and interposed be-

tween the outer end of the casing 11 and a nut 13, I provide a stop member 14, the function of which will be hereinafter described.

5 The valve actuating mechanism is designed to coöperate with the closure mechanism for closing the mouth-piece. The closure mechanism illustrated forms the subject of a pending application filed February 10, 1913, Serial Number 746,889.

15 As shown herein, and as more fully described in the pending application above, the door 15 of the closure means is movable with and supported from locking members 16, the door being connected with said members by means of bent arms 17 and tension springs 18, the latter having their outer ends connected with the bent arms and their inner ends secured to apertured lugs 19 formed integral with the door.

20 Located at one side of the mouth-piece and supported therefrom by means of a projecting bracket 20, is a latch mechanism comprising part of the locking mechanism.

25 The latch mechanism is shown as comprising a latch member proper 21 having apertured bent ends adapted to be respectively mounted on parallel rods 22, the latter projecting outwardly from and carried by a pin 23 formed integral with the bracket 20.

30 The outer reduced ends of the rods 22 are connected by a member 24, and interposed between member 24 and the bent portions of the latch member 21 and surrounding each of the rods 22, is a compression spring 25.

35 When the door is in closed position against the front face of the mouth-piece, the connected contacting ends of the locking members 16 are in engagement with the spring controlled latch member 21, and the door is maintained tightly against the mouth-piece. When the door is in its closed position, as particularly shown by Fig. 2, the stop member 14 carried on the shaft 10 is in contact

40 with the spring controlled latch mechanism preventing the latch member 22 from being swung out of engagement with the locking member to permit the door to be opened until the valve actuating mechanism has been moved to close communication between the retort and the stand-pipe.

45 The valve mechanism *per se* disclosed herein is claimed in my application, Serial No. 869,231, filed October 29, 1914.

50 65 What I claim is:—

1. The combination with a retort mouth-piece, and a stand-pipe adapted to communicate therewith, closure means for the mouth-piece, and a valve for controlling the 60 passage between the stand-pipe and mouth-

piece, of means interposed between the valve and said closure means for controlling the movements of the closure means, said controlling means including latch mechanism ineffective to prevent movements of the valve to closed position at will and effective to prevent movement of the closure means to open the mouth-piece prior to movements of the valve toward its seating position. 65

2. The combination with a retort mouth-piece and a stand-pipe adapted to communicate therewith, closure means for the mouth-piece, a valve controlling the passage between the stand-pipe and mouth-piece, a valve stem having a stop-member, controlling means for the mouth-piece closure said controlling means including a latch co-acting with the stop-member, said co-action between the latch and stop-member being ineffective to prevent movements of the valve at will 70 and effective to prevent movement of the closure means to open the mouth-piece prior to movement of the valve toward its seating position. 75

3. The combination of a stand-pipe, a retort mouth-piece adapted to communicate therewith, a valve controlling such communication, a retort closure, means for operating the valve independently of the closure, and means coöperating with the valve 80 and said closure and operating to prevent opening of the latter when the valve is unseated. 85

4. The combination of a stand-pipe, a retort mouth-piece adapted to communicate 90 therewith, a valve controlling such communication, a retort closure, means adapted to open and close the valve independently of the retort closure, and a closure locking device actuated by the valve operating means 100 and moved thereby into closure locking position when the valve is unseated. 105

5. The combination of a retort mouth-piece, a gas offtake adapted to communicate therewith, a valve for controlling such communication, a movable valve-actuating device at the exterior of the mouth-piece, a closure for the mouth-piece, a latch movable to and from closure-locking position, and a member projecting from said valve-actuating device and moved by the latter into position to obstruct the closure-releasing movement of the latch. 110

In testimony whereof I affix my signature in presence of two witnesses.
